HOLLOW ONE-PIECE DOORKNOB AND SPIN-
DLE ATTACHMENT BUSHING ASSEMBLY

Fred Kaiser, Brooklyn, N. Y.

Application June 26, 1952, Serial No. 295,797

2 Claims. (Cl. 292—347)

1

This invention relates to improvements in door knobs; and the invention has reference, more particularly, to a hollow door knob formed in one piece from sheet metal and provided with a spindle attachment bushing affixed thereto in unitary relationship therewith.

Methods have heretofore been developed and are now known to the art whereby to produce hollow door knobs in one piece from sheet metal. Such knobs comprise a hollow knob body having an integral tubular, endwise open, shank or neck for the reception and attachment thereto of a bushing by which the knob can be operatively coupled to the spindle of a door latch mechanism. Since such knobs are of one piece, so that access to the interior thereof cannot be had once a bushing is inserted in the shank or neck thereof, considerable difficulty has been experienced in forming a strong and rigid attachment of the bushing to the knob in unitary, non-loosening relation to the latter.

Having the above in view, it is an object of this invention to provide in combination with a hollow, one-piece sheet metal door knob, a spindle attachment bushing including novel cooperative means whereby the bushing and knob are rigidly united in strong, interlocked together, unitary relationship, free from risk of loosening or of relative play.

Another object of the invention is to provide an interlocked assembly of hollow, one-piece door knob and spindle attachment bushing, wherein the bore of the bushing is closed at its inner end so that, when the knob and bushing are assembled and interlocked together in unitary relationship, the interior of the knob is sealed off against undesirable access thereto of plating or other liquids, especially when finishing the assembly during manufacture thereof.

The above and other objects of this invention will be understood from a reading of the following detailed description of the invention in connection with the accompanying drawings, in which:

Fig. 1 is a side elevational view of a hollow, one-piece sheet metal door knob and of a spindle attachment bushing therefor as opposed to the open end of the knob shank ready for insertion therein, said knob and bushing having cooperative means according to this invention for uniting the same in interlocked together assembled relation; Fig. 2 is a side elevational view in part section, showing the bushing inserted in the knob shank ready to be secured thereto; and Fig. 3 is a view similar to that of Fig. 2, show-

2

ing the bushing secured to the knob shank in unitary interlocked relation thereto.

Fig. 4 is a vertical longitudinal sectional view, taken on line 4—4 in Fig. 3; and Fig. 5 is another vertical longitudinal sectional view, taken on line 5—5 in Fig. 4.

Fig. 6 is a bottom end elevational view of the assembled and united knob and bushing.

Similar characters of reference are employed 10 in the hereinabove described views, to indicate corresponding parts.

Referring to the drawings, the reference character 10 indicates the hollow knob body having an axially projecting, outwardly open, tubular shank portion 11, all as formed from sheet metal 15 in one piece.

The reference character 12 indicates the main body of a spindle attachment bushing, the external diameter of which corresponds to the internal diameter of the tubular shank portion 11 of the knob body. The lower or outer end of the bushing body 12 is provided with an axially extending boss 13 of reduced diameter, whereby to provide the lower or outer end of the main body 12 of the bushing with an annular horizontal shoulder or seat 14 between the periphery of said main body and the periphery of said boss 13. The axial extent or height of said boss 13 substantially corresponds, preferably, to the thickness of the sheet metal from which the knob 10 and its shank portion 11 is produced. Formed integrally with the main body 12 of the bushing is at least one radially projecting horizontal lock tongue 15, the under side of which is flush with the plane of said shoulder or seat 14. Preferably two such lock tongues 15 are provided to project respectively from diametrically opposite sides of the bushing body 12.

If the knob is to be journaled in a rose mounted 40 on a door to be served by the knob, the bushing body 12 is further provided with a hub 16 of reduced diameter which is formed integrally therewith to project axially from its lower or outer end.

Indenting the marginal portions of the outer 45 end of the shank portion 11 of the knob are one or more notches 17 for the reception of the lock tongues 15 of the bushing body 12. Each lock notch 17 corresponds in width to the width of a lock tongue 15, and in depth to the height or thickness of a lock tongue plus the width of the shoulder or seat 14 with which the lower end of the main body 12 of the bushing is provided.

To mount the bushing in operative assembled 50 relation to the knob, the main body 12 of the

former is inserted into the open end of the shank portion 11 of the latter, in such manner that the lock tongue or tongues 15 of the one enter the lock notch or notches 17 of the other, and so as to be stopped therein whereby to limit the movement of the bushing into said shank portion, and thereby to predetermine the operative assembled position of the bushing relative to the knob (see Fig. 2).

When the bushing is thus initially assembled with the knob, free marginal edge portions 18 of the shank portion 11 will project outwardly beyond the shoulder or seat 14 of the bushing body 12 (again see Fig. 2). To complete the affixing of the bushing in operative assembled relation to the knob, said projecting free marginal edge portions 18 of the shank portion 11 are turned or rolled to extend angularly inward over and upon said shoulder or seat 14, thereby forming angular keeper flanges or lips 19 (see Figs. 3 and 5), and thus firmly interlocking the bushing and knob together.

It will be obvious that the described interlocked relation of the bushing and knob so affixes these parts together that there is no possibility of relative movement or loose play therebetween; since the abutment of the lock tongue or tongues 15 against the bottoms of the lock notch or notches 17 prevents inward axial movement or play of the bushing relative to the knob shank; the engagement of the keeper flanges or lips 19 with the shoulder or seat 14 prevents outward axial movement or play of the bushing relative to the knob shank; while the embrace of the lock tongue or tongues 15 of the bushing by the sides of the lock notch or notches 17 of the knob sleeve prevents rotative movement or play of the knob relative to the bushing.

The interlocking elements are all external, and consequently are readily accessible for manipulation in effecting assembly of the bushing and knob; thus saving both time and labor in knob production.

The bushing is provided with an axially extending, outwardly open bore 20 for the reception of a door latch spindle to which the knob is connected in use. This bore 20 may be of any known type or form, i. e. it may be of square cross-sectional shape, as shown; or of oval or other irregular cross-sectional shape; or of cylindrical internally screw-threaded form. As shown, the inner end of said bore 20 is preferably closed by an end wall 21, thus sealing off communication between the same and the interior of the hollow knob body 10. This is very desirable since it prevents undesirable access to the interior of the hollow knob body of plating or other liquids in providing the knob with an exterior finish during production thereof.

Having now described my invention, I claim:

1. The combination with a hollow one-piece

sheet metal door knob having an outwardly open tubular shank of a spindle attachment bushing telescoped into said knob shank, and means to interlock said bushing in fixed assembly with the shank, said means comprising a boss of reduced diameter extending axially from the outer end of the bushing to form an annular transverse seat between the periphery of the bushing and said boss, the axial height of said boss substantially corresponding to the thickness of the sheet metal by which the knob shank is formed, at least one lock tongue of substantial width projecting radially from the periphery of the bushing parallelly flush to said seat, the free marginal edge portion of the knob shank being indented by a lock notch by which said lock tongue is embraced, whereby to retain the bushing against both inward axial and rotative movements relative to the knob shank, and marginal edge portions of the knob shank being inturned over and upon said seat of the bushing to provide angular keeper means to fit said bushing against outward axial movement relative to the knob shank.

2. The combination with a hollow one-piece sheet metal door knob having an outwardly open tubular shank of a spindle attachment bushing telescoped into said knob shank, and means to interlock said bushing in fixed assembly with the shank, said means comprising a boss of reduced diameter extending axially from the outer end of the bushing to form an annular transverse seat between the periphery of the bushing and said boss, the axial height of said boss substantially corresponding to the thickness of the sheet metal by which the knob shank is formed, lock tongues of substantial width projecting radially respectively from diametrically opposite sides of the periphery of the bushing parallelly flush to said seat, the free marginal edge portions of the knob shank being indented by lock notches respectively disposed to embrace the respective lock tongues, whereby to retain said bushing against both inward axial and rotative movements relative to the knob shank, and marginal edge portions of the knob shank being inturned over and upon said seat of the bushing to provide angular keeper means to fix said bushing against outward axial movement relative to the knob shank.
